UNITED STATES PATENT OFFICE

2,085,592

FEEDING MECHANISM FOR PRINTING
PRESSESAlexander T. Koppe, New York, N. Y., assignor
to General Printing Ink Corporation, New
York, N. Y., a corporation of Delaware

Application January 11, 1934, Serial No. 706,188

39 Claims. (Cl. 271—28)

This invention relates to feeding mechanism for printing presses and its purpose is to provide improved apparatus for properly aligning and feeding paper sheets successively to the cylinders of a press. The principal object of the invention is to provide feeding mechanism comprising a series of paper-gripping devices movable in rotary paths and adapted to pick up successive sheets of paper from a stack and deliver these sheets successively to conveying apparatus leading to the printing cylinders, in such a manner as to gain greater precision of operation and greater speed of delivery as compared with the feeding devices heretofore employed in connection with printing presses. A further object of the invention is to provide paper feeding mechanism comprising a rotary head carrying a plurality of suction devices adapted to engage and automatically pick up successive sheets of paper from a stack during the rotation of the head. Still another object of the invention is to provide improved means for supporting a stack of paper sheets and automatically maintaining the upper sheet in approximately the same plane as the pile is gradually lowered by the operation of the feeding mechanism. Another object of the invention is to provide paper feeding mechanism comprising a movable head carrying a plurality of series of suction devices in combination with controlling means whereby the suction devices operate automatically in one position to engage and pick up a sheet of paper and are actuated automatically in another position to release the sheet of paper and deliver it to the conveying mechanism by which it is moved to the cylinders of the press. Still another object of the invention is to provide improved means for aligning the sheets of a stack of paper and maintaining the forward edges of the uppermost sheets in proper condition to be engaged by movable paper gripping devices. Another object of the invention is to provide a paper support having improved means for automatically moving it to correspond with the rate of feed of paper therefrom. A further object of the invention is to provide a movable paper support in combination with paper aligning devices which are adjustable to accommodate sheets of paper of different sizes. Another object of the invention is to provide paper feeding mechanism comprising a rotary head having a plurality of suc-

tion tubes each carrying a series of suction cups capable of being rendered operative or inoperative at the will of the operator. A further object is to provide paper feeding mechanism comprising a rotary head having a suction tube carrying a series of suction cups each made up of telescoping parts adapted to move by gravity into engagement with the paper sheet in a predetermined position of the head whereby the suction acting through the tube causes the paper sheet to be automatically picked up by the cup. Another object of the invention is to provide paper feeding mechanism comprising a vertically movable paper support in combination with improved power driven means for effecting the elevation thereof and manually operated means for adjusting the elevation of the table and effecting a rapid lowering movement thereof. Other objects relate to various features of construction and arrangement which will appear more fully 20 hereinafter.

The nature of the invention will be understood from the following specification taken with the accompanying drawings, in which one embodiment is illustrated. In the drawings, 25

Fig. 18 is an enlarged vertical section taken on the line 18—18 of Fig. 15;

Fig. 19 is a detail vertical section taken on the line 19—19 of Fig. 18;

Fig. 20 is a somewhat diagrammatic vertical section through the upper part of the improved feeding mechanism, taken on the line 6—6 of Fig. 1, showing the condition of the pile of sheets when the controlling finger of the feeding mechanism is resting thereon and illustrating one series of suction cups carried by the movable head approaching the position wherein they engage and pick up the uppermost sheet;

Fig. 21 is a sectional view like that of Fig. 20 showing the relative positions of the parts at a slightly later stage of the operation, wherein the finger of the controlling device has been elevated from the stack of sheets and one series of suction cups has been moved into position to engage the forward edge of the uppermost paper sheet;

Fig. 22 is a sectional view similar to those of Figs. 20 and 21, showing the relative positions of the parts at a still later stage of the operation wherein the uppermost paper sheet has been moved by the rotary head to a position where the forward edge thereof is engaged by the paper conveying mechanism of the press;

Fig. 23 is a rear elevation of the upper end of the front blower which directs a jet of air against the upper forward edge of the stack of sheets in order to project the forward edge of the uppermost sheet upwardly in position to be readily engaged by the suction cups; and

Fig. 24 is a perspective view of the paper holding device which engages the rear upper edge of the stack of sheets to prevent the removal of more than one sheet at a time.

As illustrated in the drawings, the invention comprises a base 30 having longitudinal side members 30a and transverse members 30b which are secured to the floor or other support. The

side members 30a of the base have metal side frame members 31 secured thereto and extending upwardly therefrom in parallel relation to support the principal parts of the paper feeding mechanism constituting the present invention. Mounted between the side frame members 31 is a table or shelf 32 adapted to support a stack of paper sheets 33, shown in Figs. 20, 21, and 22, which are removed successively from the stack by a rotary suction head 35 arranged to deliver the sheets to the conveying apparatus 36 by which they are carried rearwardly in the printing press to the printing cylinders. The table 32 is carried by a pair of angle bars 37 which are mounted upon blocks 38. These blocks 38 are provided with T-shaped slots 38a, shown in Fig. 8, which have a sliding engagement with the T-shaped guide members 39 carried by the side frame members 31. In this instance, the guides 39 are formed by securing plates 39a to the inner edges 20 of ribs 39b which are formed integrally with the side frame members. The vertical adjustment of these blocks 38 along the guides 39 is effected by a pair of adjusting screws 40 which threadedly engage the internally threaded apertures 38b of the blocks and are mounted at their upper ends in bearings 41 carried at the upper ends of the frame members 31. These adjusting screws 40 are rotated by the mechanism hereinafter described. In order to limit the downward movement of the blocks 38 and thereby prevent disengagement of these blocks and the adjusting screws 40, the lower ends of the guides 39 are provided with inwardly extending brackets 42 having vertical stop pins 43 mounted therein, as shown in Fig. 2. Coil springs 44 are mounted between the heads of these pins and the brackets, and the upward movements of the pins are limited by cotter pins 45 extending transversely through the lower ends thereof. This construction thus provides a resilient stop for the blocks 38 and the table 32 at the lower end of their path of travel. The table 32 is provided on its under side with socket members 46 which receive the spherical balls 47 arranged to rest upon the lower horizontal flanges of the angle bars 37, as shown in Fig. 2. This enables the table 32 to be freely adjusted upon its immediate support in order that the pile of paper sheets 33 may be properly aligned with their lateral edges in the proper vertical planes when the pile is first placed in the press. For the purpose of effecting this adjustment, a bar 48 is mounted to extend transversely between the vertical flanges of the bars 37 and this bar is provided with elongated slots 48a engaged by bolts 49 which project downwardly from the under side of the table 32 with their lower ends engaged by wing nuts 50 for clamping the table in the desired position with respect to the bar. When these clamping nuts 50 are loosened, the table may be shifted transversely of the press with respect to the bar 48 by means of a pinion 51 rotatably mounted on the under side of the table and arranged to engage rack teeth 52 which are formed along one edge of the bar 48. The pinion 51 may be turned by a handle 53 for the purpose of effecting the desired lateral adjustment of the table 32 before the wing nuts 50 are tightened to hold it in adjusted position.

The pile of paper sheets 33 is placed upon the table 32 when this table is removed from the press and then, when the table is placed in the press with the stack of paper sheets piled thereon, it is moved in a forward direction along the angle bars 37 until the forward edge of the table 75

and the forward edges of the paper sheets, which are in alignment therewith, engage the front vertical guide posts 55 which are secured in fixed position on transverse frame members 56 extending between the side frame members 31, as illustrated particularly in Figs. 2 and 6. The table 32 is then secured in this position by a pair of locking levers 57 which are pivoted at 58 on the supporting blocks 38 and which are capable of being swung upwardly to engage slots in the lower ends of angle-shaped brackets 59 which are secured to the under side of the table 32 and arranged with their vertical flanges extending downwardly parallel to the inner faces of the blocks 38. These locking levers 57 are adapted to be held in the position shown in Fig. 2 by spring clips 60 which have the form shown particularly in Fig. 7. Each spring clip is secured to the adjacent bracket 59 by screws or the like and is provided with a pair of side arms 60^a having inwardly turned resilient extremities 60^b which permit the lever 57 to be snapped between them in either direction although normally maintaining the lever in engagement with the slot of the adjacent bracket 59 so that the table 32 is properly positioned to cause the pile of sheets 33 thereon to move vertically with their forward edges in contact with the guide posts 55. When the table 32 has thus been properly positioned with respect to the posts 55, it may be shifted transversely in the manner hereinbefore described in order to position the lateral edges of the sheets in the proper vertical planes and this is effected by bringing them into engagement with a lateral guide member 61 which engages one edge of the pile of sheets at the forward corner thereof, as illustrated in Figs. 1 and 2. This lateral guide member 61 is carried by a block 62 which is slidably mounted upon the lower transverse frame member 56, being secured in adjusted position thereon by means of a locking screw 63 so that it may be adjusted transversely of the feeding mechanism to accommodate sheets of different sizes. These guides 55 and 61, engaging two right angularly disposed edges of the pile of paper sheets, are sufficient to position the pile accurately in the machine but additional means are provided for engaging the uppermost portions of the stack of sheets on all four sides to insure even greater accuracy in the positioning of the sheets as they are removed successively from the top of the stack.

For this purpose, there are provided a pair of side guides 65 which are in the form of bars extending downwardly and engaging the lateral edges of the uppermost sheets of the stack. These guide members are carried by rods 66 which are slidably mounted in brackets 67 carried by the upper ends of the side frame members 31, as shown particularly in Figs. 4 and 15. Each rod 66 may be moved longitudinally and turned in its bearing and held in adjusted position by set screws 68 in order to cause the connected guide members 66 to assume the desired angle and to engage one lateral edge of the pile of paper sheets adjacent the top thereof. In addition to these side guides 66, there are provided two rear guide members 70 having vertical portions 70^a which engage the upper rear edges of the stack of sheets and having horizontal portions 70^b which extend rearwardly from the upper part of the stack and are slidably mounted in blocks 71. The guide members 70 are secured in adjusted position in the slots of these blocks 71 by means of clamping screws 72 and the blocks are provided with bosses

71^a which are apertured for sliding engagement with a pair of rods 73 extending transversely of the machine and secured at their ends by angle plates 74 which rest upon and fit against the inner sides of the upper flanges 31^a of the side frame members, as illustrated in Figs. 1 and 2. A set screw 75 engages the vertical flange of one of these angle plates 74 and bears against the adjacent vertical surface of the side frame member 31 to secure the bars 73 in the desired position rearwardly of the machine. By adjusting the position of the angle plates 74 on the side frame members 31 and by adjusting the positions of the horizontal portions 70^b of the guide members in the blocks 71, the depending portions 70^a of the guide members may be caused to occupy the desired vertical plane for engaging the rear edges of paper sheets of varying sizes. As the table 32 is elevated and the paper sheets are successively removed therefrom by the operation of the feeding devices hereinafter described, the depending portions 70^a of the rear guide members will eventually engage the slots 32^a which are provided in the table for accommodating them as the table approaches its extreme upper position. At a point between the rear guide members 70 and their supporting blocks, there is mounted a rear edge weight or retaining member 77 having the form illustrated particularly in Figs. 1, 20, and 24. This member comprises a bar 77^a having its forward end directed downwardly and secured to a rubber block 77^b which rests by gravity upon the rear edge of the uppermost sheet of paper as shown, for example, in Fig. 20. The rear end of the bar 77^a is secured to a block 77^c having its lower surface provided with a semi-circular bearing portion 77^d adapted to fit the upper side of the rear supporting rod 73 when the block 77^c is placed thereon. The rear end of the retaining member is thus pivotally mounted upon the bar 73 and the forward end rests upon the rear edge of the uppermost paper sheet so that when the top sheet is withdrawn in a forward direction in the manner hereinafter described, this weight will immediately engage the next sheet of the pack 45 and prevent it from being withdrawn also by frictional contact with the upper sheet or because of static electricity which may be developed in the pile of sheets.

In order to facilitate the removal of the uppermost sheet from the stack by the suction devices hereinafter referred to, means are provided for projecting jets of air under pressure against the forward edges and the forward portions of the lateral edges of the uppermost sheets of the stack, 55 thus turning the forward edge of the uppermost sheet upwardly away from the stack in position to be readily engaged by the suction devices of the rotary head 35. As shown in Figs. 2, 6, and 23, a tube 80, of rectangular cross-section, is 60 mounted vertically midway between the side frames 31 with the upper portion thereof clamped to one of the transverse frame members 56 by means of bolts 81, a bar 82 and wing nuts 83. The upper end of this tube diverges laterally to 65 form a pair of arms 80^a which are closed except for vertical slots 80^b formed therein, as shown in Fig. 23, opposite the forward edges of the uppermost sheets of the stack. The tube 80 is connected by a flexible hose 84 to a source of compressed air, as hereinafter described, so that at the instant when the uppermost paper sheet is about to be engaged by the suction cups of the rotary head 35, a blast of air is injected through the tube 80 to force upwardly the forward edge of 70

the uppermost sheet. This action of the jets of air from the tube 80 is augmented by other jets of air from tubes 85 which have their ends 85^b directed inwardly toward the ends of the uppermost sheets of the stack and are provided with slots 85^b through which jets of air are directed against the ends of the uppermost sheets at the same time that the jets are caused to impinge upon the sheets from the tube 80. Each tube 85 is mounted upon a pipe 86 which is slidably and rotatably mounted in one of the brackets 61 previously referred to and arranged to be held in adjusted position by a set screw 87, as shown in Fig. 4. Compressed air is supplied to each of the pipes 86 through a flexible conduit 88 leading from the source of compressed air supply and by adjusting the pipes 86 in the brackets 61, the slots 85^b through which the air is projected against the paper sheets may be located in proximity to the ends of the uppermost sheets of paper stacks of various sizes.

Before describing the mechanism by which the table 32 is raised and lowered, the mechanism by which the paper sheets are removed from the stack 33 and delivered by the rotary head 35 to the conveying mechanism 36 will be described. The rotary head, shown particularly in Figs. 9, 10, and 10a, comprises a shaft 90 journaled at its ends in brackets 91 and 92 which are secured to the tops of the side frame members 31. At the right hand end of the shaft 90, as viewed in Figs. 1 and 9, a nut 93 is secured on the projecting threaded end of the shaft on the outer side of the bracket 91, and on the inner side of this bracket a disk 95 is secured on the shaft to rotate in contact with the face of the bracket. This disk is provided with a pair of inwardly projecting bosses 95^a in which are mounted the ends of suction tubes 97. The two tubes illustrated in this embodiment are located on opposite sides of the shaft 90 and their right hand ends, as shown in Fig. 9, are normally closed by the face of the bracket 91 which has a circular flange 91^a surrounding the outer edge of the disk 95. The bracket 91 has an angular passage 91^b formed in the lower part thereof to communicate with the end of either tube 97 when this tube is in its lowermost position and this passage extends along the face of the bracket as shown at 91^c in Fig. 10, so that communication is maintained with a tube 97 through a certain arc of its rotary movement during the rotation of the shaft 90. A suction pipe 88 is connected to the lower end of the passage 91^b and extends downwardly on the inner side of the adjacent side frame 31 to communicate with the valve casing 103 through which the pipe 98 is connected with a pipe 101 leading from a vacuum pump or the like, as shown in Fig. 8. At the left hand side of the machine, as viewed in Figs. 1 and 9, the shaft 90 carries an arm or cross-head 102 in which the ends of the vacuum tubes 97 are mounted and sealed against communication with the atmosphere by plugs 103 so that when the suction line is connected to these tubes 97 at their other ends, the air is withdrawn therefrom at certain periods during their rotation. The end of the shaft 90 which is journaled in the bracket 92 is connected to the mechanism by which the head 35 is rotated, as shown in Figs. 9 and 18.

The head 35 is rotated in the direction indicated by the arrows 104, shown in Figs. 6, 20, 21, 22, and 23, and the suction which is applied through the tubes 97 is adapted to pick up the paper sheets 76 successively from the stack 33 through the opera-

tion of vacuum cups 105 which are mounted on the tubes 97 in the manner shown particularly in Figs. 9, 10, 10a and 17. The vacuum cups 105 are mounted upon sleeves 106 which are placed end to end upon the tubes 97, each tube 97 having mounted thereon a central fixed sleeve 106^a and two longer adjustable sleeves 106^b mounted on opposite sides thereof. The sleeves 106^b are adjustable endwise of the tubes and are adapted to be held in adjusted positions by clamps 107 which are secured thereto and which are slidably longitudinally of rods 107^a which extend parallel to the tubes with their ends fixed in the disk 95 and the head 102. Each clamp 107 has a pair of spaced ears 107^b connected by a clamping screw 107^c and this screw may be tightened for the purpose of securing the clamp on the rod 107^a and thereby holding the connected sleeve 106^b against endwise movement. As shown particularly in Fig. 17, each vacuum cup comprises a tubular stem 108 which threadedly engages another aperture in the wall of the adjacent sleeve 106. The outer end of each stem 108 is internally threaded for engagement with a plug 109 having a central bore 109^a and an annular flange 109^b which projects outwardly beyond the periphery of the stem 108. A tube 110 is slidably mounted on the stem 108 and has an annular shoulder 110^a adapted to engage the projecting flange 109^b of the plug 109 to limit the movement of the tube 110 radially outward from the axis of the supporting sleeve 106. At its outer end, the tube 110 is internally threaded for engagement by a paper-engaging member or cup 111 which may have an annular ring of rubber for engagement by the paper sheet but which, in this embodiment, is constructed as a metallic member having a threaded neck which engages the threaded portion of the tube 110, and a transversely extending disk 111^a having an annular knurled surface 111^b which may be engaged by the fingers of the operator to permit its insertion in or removal from the tube 110. The central portion of this disk 111^a is provided with a series of relatively small apertures 111^c through which the suction exerted through the cup 105 may operate upon the surface of the paper sheet so that the paper sheet will be held against the outer face of the disk by the surrounding atmospheric pressure and thus permit the paper sheet to be picked up by the cup during the rotation of the tubes 97 with the head 35. The vacuum cup 105 is of a form described and claimed in my co-pending application Serial No. 612,988, filed May 23, 1932, which has now matured into United States Patent No. 1,990,334, dated February 5, 1935.

Each tube 97 is provided with a central port 97^a, located on its outer side, to communicate with the stem 108 of a vacuum cup 105^a mounted on the adjacent fixed sleeve 106^a. In addition, each tube 97 has formed therein on each side of the port 97^a, three other ports 97^b, 97^c, and 97^d which are adapted to communicate respectively with the hollow stems of three vacuum cups 105^b, 105^c, and 105^d which are carried by one of the adjustable sleeves 106^b. All of the ports formed in each tube 97 are located in alignment with each other longitudinally of the tube and each of the ports 97^c and 97^d are elongated to a considerable extent longitudinally of the tube so that they establish a communication with the vacuum cups 105^c and 105^d, respectively, throughout a considerable range of adjustment of the sleeve 106^b by which these vacuum cups are carried. With this arrangement, a sleeve 106^b may be secured by the

clamp 107 in its innermost position, as shown in Fig. 10a, wherein the stem of the vacuum cup 105^b does not register with the port 97^b so that this cup is rendered inoperative, while at the same time both of the cups 105^c and 105^d are permitted to function because the stems of those cups then register, respectively, with the ports 97^c and 97^d. The length of the ports 97^c and 97^d is such that when the sleeve 106^b is adjusted to bring the vacuum cup 105^b into registry with the port 97^b, all three cups carried by the sleeve 106^b will operate in picking up a paper sheet from the stack. When a sleeve 106^b is adjusted to its outer position on a tube 97, both of the vacuum cups 105^b and 105^c register with the ports 97^b in the supporting tube 97 and the cup 105^d registers with the port 97^d, thus permitting all three of these cups to operate when they are spaced at greater distances from the central cups 105^a. It will be apparent that the clamps 107, in addition to holding the sleeves 106^b against rotation, permit these sleeves to be secured in various adjusted positions which will render any desired number of vacuum cups operative for engaging paper sheets of various widths.

It sometimes happens, particularly when employing paper sheets 33 which are relatively thick, that the forward edges of the uppermost sheets will curl upwardly to a slight extent, thus making it more difficult for the vacuum cups 105 to take hold of the sheets as the head 35 rotates. To overcome this difficulty, the vacuum cups 105 may be made adjustable angularly about the tubes 97 and for this purpose the tubes are flattened on the sides where the elongated ports are located as shown at 97^e in Figs. 10b and 17. These flattened portions extend throughout the length of each of the ports 97^b, 97^c, and 97^d. The clamps 107 are provided with elongated circumferential slots 107^e engaged by the screws 107^f which secure the tubes 106^b to the clamps. By loosening these screws 107^f, the sleeves 106^b may be turned angularly on the tubes 97 to effect a corresponding angular adjustment of the vacuum cups 105^b, 105^c, and 105^d so that the ends of these cups will properly engage the forward edges of the curled paper sheets. The flattened surfaces 97^e permit the ports in the tubes 97 to maintain their communication with the vacuum cups 105, even when the cups are turned, as shown by dotted lines in Fig. 17, and when the adjustment has been made, the screws 107^f may be tightened to hold the cups in the inclined positions. A similar construction may be provided for adjusting the central cup 105^a on each tube, if desired.

In Fig. 20, the rotary suction head 35 is shown in a position wherein the series of cups 105 carried by the lower tube 97 are moving downwardly toward the forward edge of the uppermost paper sheet of the stack and, when in this position, the suction is cut off from the tubes 97 and the compressed air is also shut off from the blower tubes 80 and 85. As the head 35 continues its rotation from the position shown in Fig. 20, the valve mechanism in the casing 100 is automatically operated to establish a connection between the compressed air supply line 112 and the compressed air pipes 113, shown in Fig. 8. These pipes 113 communicate with the flexible conduits 88 through controlling valves 114 so that compressed air is discharged from the blower nozzles 85 at the sides of the forward edges of the uppermost paper sheets. At the same time a connection is established from one of the pipes 113 through a flexible conduit 84 to the lower end

of the blower pipe 80 so that compressed air is discharged through the slots 80^b of this pipe against the forward edges of the paper sheets, causing them to be slightly elevated with the forward edge of the uppermost sheet lying above the upper ends of the guide posts or stakes 55. As the lower vacuum tube 97 approaches the position shown in Fig. 21, the valve apparatus in the casing 100 operates automatically to establish a connection between the suction line 101 and the pipe 99 so that when the end of the lower tube 97 establishes communication with the passage 91^b in the face of the bracket 91, as shown in Fig. 9, the suction becomes effective in the cups and as the axes of the lower series of vacuum cups 105 approach the vertical position shown in Fig. 21, the tubes 110 of these vacuum cups slide downwardly by gravity and cause the paper engaging members 111 to contact with the upper surface of the forward portion of the uppermost paper sheet of the stack. As soon as this occurs, the paper sheet seals the openings 111^c at the mouths of the cups, whereupon the outside atmospheric air acting on the cup and the lower face of the paper sheet causes the tubes 110 of the lower series of cups to move upwardly on the stems 108 with the result that the forward edge of the paper sheet is elevated from the stack. Then, as the rotation of the head 35 continues in the direction of the arrow 104, the upper paper sheet is drawn forwardly from the stack as shown in Fig. 22, and this continues until the forward edge of the sheet is engaged and held by the conveying mechanism 36, at which instant the vacuum in the lower tube 97 of the head is automatically shut off by the passage of the end of that tube 97 out of communication with the passage 91^c in the face of the bracket 91 or by the automatic operation of the valve mechanism in the casing 100. As the uppermost sheet is withdrawn from the stack, the rear edge of the next lower sheet is engaged by the retaining member 71 so that it is not also withdrawn by reason of frictional contact with or attraction by the uppermost sheet.

When the width of the paper sheets being fed is such that all of the vacuum cups 105 are not being used, it may be desirable to prevent the reciprocation of the tubes 110 on the stems 108 of those vacuum cups which are not active and this may be done by employing the form of clamp shown in Fig. 17a, comprising a U-shaped clamping member 115 which is somewhat resilient and which has curved extremities 115^a adapted to embrace the opposite sides of one of the tubes 97. The arms of this clamping member are embraced by a yoke 116 which is adapted to fit over one of the vacuum cups 105 and which has one side thereof secured to one side arm of the clamp. An adjusting screw 117 engages the other wall 60 of the yoke and may be manipulated to cause the curved extremities 115^a of the clamp to grip the tube 97 and thus hold the clamp in place over one of the vacuum cups 105. The cross bar of the clamp carries a cup-shaped rubber member 118 which fits over the end of the vacuum cup and seals the holes 111^c while at the same time securing the tubular portion 110 of the vacuum cup in its retracted position. When one of the vacuum cups is in communication with the interior of the connected vacuum tube 97, it may be rendered inoperative temporarily by putting a sheet of adhesive tape over the holes 111^c, whereupon the atmospheric pressure acting on the

outside of the cup will cause the tubular portion 118 to be retained in its retracted position.

The conveyor mechanism 36 by which the paper sheets are fed forwardly to the cylinders of a printing press comprises a pair of rollers 120 which are spaced apart at the center of the machine and secured upon a shaft 121 having bearings in brackets 122 which are secured upon the upper edges of the side frames 31. These rollers are adapted to cooperate with two other similar rollers 128 which are secured upon another shaft 124 which is located forwardly of the shaft 121 and which also has bearings in the brackets 122. These shafts are connected through an intermediate idler shaft 119 and connected gears 119a, as shown in Fig. 6, so that they rotate in unison in the same direction. A series of endless conveyor belts or tapes 125 extends rearwardly over the end of a metal surface or feed table 126 of 20 which only a portion is shown in the drawings, and each of these tapes extends around one of the rollers or pulleys 120 or 128 so that as these rollers rotate in the direction indicated by the arrow 127, the tapes move forwardly over the 25 surface of the table 126 and are adapted to carry therewith the paper sheets which are fed thereto by the rotary head 35. The table 126 is provided with a rectangular notch 126a in its forward edge which accommodates the two rollers 120 which 30 are positioned on the shaft 121 and those portions 126b of the forward edge of the table which are located on opposite sides of these rollers are inclined downwardly toward the upper portion of the lower tube 88, as shown in Fig. 6, so that they 35 direct upwardly the forward edges of the paper sheets which are being moved into engagement with the rollers 128. The positions of the inclined portions 126b of the table are such that the vacuum cups 105 may swing thereover even when 40 the tubes 110 are in their lower positions and the central cup 105a, when extended, may swing freely between the two rollers 128. The table 126 is also provided with apertures 126c which 45 permit the upper peripheral portions of the rollers 128 and the endless tapes 125 which engage these rollers to extend upwardly through the table.

The rollers 120 are driven by mechanism connected to the shaft 121 as hereinafter described and rotates in the direction indicated 50 by the arrow 127 in Figs. 6, 20, 21, and 22. As the forward edge of the paper sheet is delivered to the rollers 128, as shown in Fig. 22, it is engaged on its upper side by gripping rollers 128 carried by crank arms 129 which are mounted to 55 pivot about a shaft 130 extending between and journaled in the upper parts of the brackets 122 in which the shaft 121 is mounted. These crank arms 129 are bifurcated and embrace arms 131 which are fixed upon the shaft 130, as shown in 60 Fig. 1. Each crank arm 129 has a transverse member 129a coacting with one end of a coil spring 132 which engages at its other end the under side of one of the arms 131. An adjusting screw 133 engages the upper part of the crank 65 arm 129 and coacts with the upper side of the intermediate arm 131 so that the relative adjustment of these two arms may be regulated to determine the position of the connected roller 128 with a predetermined angular movement of the shaft 130. One end of the shaft 130 has a crank arm 135 secured thereon and extending downwardly therefrom with a roller 136 mounted in its lower end. This roller engages the surface of a cam 137 which is actuated as herein- 70 after described to oscillate the shaft 130 and

periodically elevate the rollers 128 from a position wherein they engage the upper surface of a paper sheet as it passes onto the rolls 120. A coil spring 138 is connected to the frame and to the arm 135 to maintain the roller 136 in engagement with the surface of the cam 137. By adjusting the screws 133 previously referred to, the relative positions of the arms 131 and 129 may be regulated to cause the rollers 128 to grip paper sheets of various thicknesses as these paper sheets are fed to the conveyor 36, as shown in Fig. 22. The cam 137 is adapted to lower the rollers 128 as the paper sheet reaches the position shown in Fig. 22 so that it is then moved by the rolls 120 and by the tapes 125 rearwardly over the apron 126. The tapes 125 are maintained in a taut condition by rollers 139 mounted on crank arms 140 which are arranged to oscillate about a shaft 141 extending between the side frames 31. Coil springs 142 are connected between the crank arms 140 and fixed supports 143 to maintain the rollers 139 in engagement with the lower runs of the tapes, as illustrated in Fig. 6.

As the paper sheets are fed to the conveyor 36, they are deflected downwardly onto the tapes 25 by guards 145 which are mounted upon a rod 146 extending between brackets 147 carried by the rear portions of the side frames 31. These guards may be adjusted in their angular positions on the rod 146 by means of set screws 144 and they are preferably located directly over two of the tapes 125, as shown in Fig. 1. The forward ends of these guards are deflected downwardly but at points removed from the peripheries of the rolls 120, as shown at 145a, so that they catch the forward edge of the paper sheet as it is fed between the rolls 120 and the gripping rollers 128. As a further means of insuring the proper passage of the paper sheet rearwardly over the apron 126 in contact with the tapes 125, a number of rollers 150 are mounted on arms 151 which are arranged to pivot about the shaft 146. These rollers 150 rest by gravity upon the surface of the paper sheet and are also pressed by leaf springs 152 engaging the arms 151 so that they hold the sheet in contact with the tapes 125.

Referring now to the means for actuating the various parts of the mechanism which have heretofore been described, it will be seen upon reference to Figs. 6 and 15 that there is provided a power shaft 155 leading from a driving motor or other source of power located adjacent the forward part of the printing press. This shaft is inclined upwardly and rearwardly and has its rear end journaled in a bearing bracket 156 which is secured to the uppermost transverse frame member 56 as shown in Fig. 6. A collar 157 is secured to the shaft at the lower end of this bearing and a beveled pinion 158 is secured thereto at the upper end of the bearing. This pinion 158 meshes with a beveled gear 159 which is mounted on a shaft 160 having the end portion thereof journaled in bearings 161 which are mounted in the side frame members 31 as illustrated particularly in Fig. 18. A driving connection is adapted to be established between the gear 159 and the shaft 160 by means of a dog 162 which is slidably mounted in a groove 159a formed in the face of the gear. This dog has a stem 162a which engages a hole 160a formed in the shaft 160, and it also has an enlarged head 162b provided with side faces 162c which converge outwardly. This head is adapted to en-

5 10 15 20 25 30 35 40 45 50 55 60 65 70 75 80 85 90 95

75

gage a recess 163^a formed in a plate 163 which is attached to the face of the gear by means of screws 164 and the inclined faces 162^c of the head are adapted to coact with the inclined wedging faces 163^b of the recess formed in the plate 163. When the dog 162 is in its outermost position with the head 163^b engaging the recess 163^a, the stem 162^a of the dog retains its engagement with the radial hole 160^a in the shaft and a driving connection is thereby established between the shaft and the gear. This driving connection is adapted to be maintained, when desired, by a cylindrical plunger 165 which engages the longitudinal bore 160^b of the shaft and which has a tapered extremity 165^a adapted to coact with the inner end of the stem of the dog 162 to force this dog outwardly into the position shown in Fig. 18. When the plunger 165 is withdrawn from the position shown in Fig. 18, the continued rotation of the gear 159 by the operation of the pinion 158 causes the inclined wedging surfaces of the plate 163 to coact with the surfaces 162^c of the dog 162 and thus force the dog inwardly to the position shown by dotted lines in Fig. 19, thereby breaking the driving connection between the gear and the shaft and permitting the gear to rotate freely thereon.

The plunger 165 is mounted on the inner end of a rod 166 and the outer end of this rod is engaged by a sleeve 167 having a pair of annular spaced flanges 167^a. A nut 168 engages the threaded outer end of the rod 166 and a coil spring 169 is mounted in the bore 160^b of the shaft between the inner end of the sleeve 167 and the outer end of the plunger 165 so that this spring tends normally to maintain the plunger 165 in its inner position. The annular groove 167^b which is formed between the flanges 167^a of the sleeve is engaged on opposite sides by lugs 170 which are secured to the bifurcated arm 171^a of a bell crank lever 171. This bell crank lever is pivotally mounted on a pin 172 extending between the ears 173^a of a bracket 173 which is attached to the outer side of one of the side frames 31 by means of studs 174, as shown in Fig. 15. The bell crank lever 171 has another arm 171^b extending outwardly from the pin 172 and having a pivotal connection by a pin 175 with a link 176. This link is in turn pivotally connected by a pin 177 with a block 178 having a pivotal connection by a pin 179 with the lower end of another link 180. The upper end of the link 180 is connected by a pin 181 with a crank arm 182 formed on a hub 183. This hub is mounted to revolve about a stub shaft 184 carried by a bracket 185 which is secured to the adjacent side frame 31 and it is secured on this shaft by a washer 186 and a screw 187 as shown in Fig. 18. The hub 183 has formed integrally therewith a crank 188 having a handle 189 projecting outwardly therefrom so that by the rotation of the hub through the operation of this crank, the bell crank lever 171 may be actuated to withdraw the plunger 165 from the position shown in Fig. 18 and thereby break the connection between the gear 159 and the shaft 160. The links 176 and 180 permit such freedom of movement as may be required in the various positions of the bell crank lever 171 and the normal position of the crank 188 is determined by a set screw 190 engaging a lug 191 projecting outwardly from a block 192 attached to the bracket 185. This set screw 190 may be secured in adjusted position by lock nuts 193.

When the gear 159 is connected to drive the shaft 160, this shaft operates to impart an intermittent rotary motion to the suction head 35 through mechanism which is illustrated particularly in Figs. 15, 16, 18, and 19. The projecting end of the shaft 160 has keyed thereon a gear 195, adapted to control the operation of the paper gripping rollers 128 and also a segmental gear 196 which is adapted to actuate the rotary head 35. This gear 196 has a series of gear teeth 196^a extending throughout substantially one-half of its periphery and the ends of the series of gear teeth are connected by a semi-circular surface 196^b which is formed as a continuation of the pitch line of the gear teeth. The teeth 196^a of this gear are adapted to mesh with the teeth 197^a of another gear 197 which is keyed on a shaft 198 located somewhat above the shaft 160 and journaled in bearings in the side frame 31 and in the bracket 173 previously referred to. The shaft 198 has fixed thereon a sprocket wheel 199 which drives a sprocket chain 200 extending in an upward direction and passed around another sprocket wheel 201 fixed on the end of the shaft 90 of the rotary suction head. For the purpose of maintaining this sprocket chain 200 in taut condition and thereby insuring an accurate positioning of the suction cups of the rotary head during its operation, the intermediate portion of the sprocket chain 200 is engaged by an idler sprocket wheel 202 rotatably mounted upon a bracket 203 which is adjustably secured to the bracket 185 by means of studs 204. By adjusting this bracket 203 on the bracket 185, the pressure of the idler 202 on the sprocket chain may be adjusted as desired to maintain the chain in a taut condition.

It will be apparent that each revolution of the gear 196 produces only a partial rotation of the gear 197 and of the shaft 198 and these gears and the sprocket wheels 199 and 201 are so proportioned as to cause the suction head 35 to rotate through 180 degrees for each revolution of the gear 196. In order to prevent shock to the apparatus and to prevent damage to the gear teeth when the teeth 196^a move into mesh with the teeth of the gear 197, the gear 196 is provided with radial shoulders 196^c which are located in diametrically opposite positions for engagement with dogs 205 which are pivotally mounted on pins 206 projecting from the face of the gear 197. These dogs have teeth 205^a which project beyond the periphery of the gear 197 to engage the shoulders 196^c and on their other sides they are provided with flanges 205^b carrying lugs 205^c which receive the ends of coil springs 207. The other ends of these coil springs are engaged by the ends of adjusting screws 208 which threadedly engage lugs 209 formed on the face of the gear 197, thus permitting the screws 208 to be adjusted to regulate the initial compression of the springs 207 which force the flanges 205^b against stop pins 210 secured in the face of the gear 197. This construction causes each shoulder 196^c of the driving gear 196 to engage a tooth 205^a of one of the dogs 205 before the endmost tooth of the series of teeth 196^a moves into mesh with the teeth of the gear 197. This causes one of the springs 207 to be compressed so that this resilient pressure has to be overcome and the gear teeth are caused to engage each other gradually without injury thereto or shock to the other parts of the mechanism. When the teeth have engaged, the gear 196 drives the gear 197 for a

half revolution and then the semicircular face 196^b of the gear 196 rides over one of the curved surfaces 197^b of the gear 197 while the latter gear remains stationary. There are two of these surfaces 197^b located on diametrically opposite sides of the shaft 198 and after the surface 196^b has been in engagement with one of these surfaces 197^b for a half revolution of the shaft 198, the gear teeth again mesh and cause another half revolution of the rotary suction head 35. During the intervals between these half revolutions of the suction head, the suction tubes 97 are located one above the other with their axes in a vertical plane so that the suction cups 105 carried by the lowermost tube 97 project directly downward, as shown in Figs. 6 and 21, so that the cups are stationary during the time when the forward edge of the uppermost paper sheet is engaged thereby and elevated from the stack 33. The gear 195, previously referred to as being keyed upon the shaft 198, meshes with a gear 214 fixed upon another shaft 215 which is journaled in bearings carried by the side frames 31 and which projects beyond the side frame at the side of the machine opposite the gear 214, as shown in Fig. 3. This projecting end of the shaft 215 has secured thereon the previously described cam 197 which actuates the crank arm 195 for raising and lowering the gripping rollers 128 in proper timed relation to the receipt beneath these rollers of the forward edges of the paper sheets which are elevated and moved forwardly from the stack by the operation of the rotary head 35. The shaft 215 also has fixed thereon a gear 216 which meshes with the gear 119^a on the shaft 121, thus driving the roller shaft 121 and the connected shaft 124.

In addition to driving the gears 195 and 196, the shaft 198 has secured to the other end thereof, on the opposite side of the other side frame, a pair of sprocket wheels 220 and 221. A sprocket chain 222 passes around the sprocket wheel 220 and extends downwardly around another sprocket wheel 223 which is fixed upon the shaft 114 of the air valve and suction valve mechanism contained within the casing 199, as illustrated in Fig. 3. This valve mechanism is therefore operated in the proper timed relation to the movements of the rotary head 35 and the gripping rollers 128. The other sprocket gear 221, fixed on the shaft 198, meshes with a sprocket chain 224 which extends rearwardly on the outer side of the adjacent side frame to drive a sprocket gear 225 which is fixed upon the operating shaft 226 of the mechanism by which the table 32 is gradually elevated, as paper sheets are removed therefrom, in order to maintain the uppermost paper sheet always at substantially the same level. This mechanism for raising and lowering the table 32 comprises the two screw shafts 46 previously referred to which are journaled at their upper ends in the bearing blocks 41 and which have worms 228 secured on their extremities, as shown in Figs. 1, 2, and 15. These worms mesh with worm wheels 229 fixed on the end portions of a transverse shaft 230 which is journaled at its ends in bearing blocks 231 mounted on the upper ends of the side frames 31. This shaft 230 extends beyond its bearings 43 at the right hand side of the machine, as viewed in Fig. 1, and has splined on the end thereof a hand wheel 232, provided with a handle 232^a, as shown in Fig. 11, by which it may be manually rotated, primarily for the purpose of effecting a quick movement of the table 32 in a downward

direction after a stack of paper sheets has been fed therefrom to the printing press. Between the hand wheel 232 and the adjacent bracket 67, the shaft 230 has rotatably mounted thereon a sprocket gear 234 which is adapted to be driven by a sprocket chain 235 extending downwardly and around a sprocket gear 236 formed on the hub of a beveled gear 237, as shown in Fig. 11. The sprocket gear 234 has an elongated hub 234^a provided at its ends with sockets 234^b adapted to be engaged by pins 232^b which are formed on the hub of the hand wheel 232. As shown in Fig. 11, the hub of this hand wheel is splined upon the reduced end portion 230^a of the shaft 230 so that it is capable of longitudinal movement thereon to disengage the pins 232^b from the sockets 234^b. The extent of outward movement of the hand wheel is limited by a disk 238 which is secured on the end of the shaft by a stud 239, and the hand wheel is normally held in its inner position by a latch member 240 which is pivoted on lugs 241 projecting from the hub of the hand wheel and which is engaged on its inner end by a coil spring 242 seated in a recess in the hub of the hand wheel so that the shoulder 240^a of the latch member is normally maintained by this spring in interlocking engagement with the inner face of the disk 238. When the hand wheel 232 is in its inner position, as shown in Fig. 11, a driving connection is established through the hand wheel from the sprocket gear 234 to the shaft 230 so that the shaft 230 may then be rotated by the sprocket chain 235 for the purpose of effecting vertical movement of the paper supporting table 32. When the latch 240 is depressed and the hand wheel is withdrawn to disengage the pins 232^b from the sockets 234^b, the hand wheel may be rotated to rotate the shaft 230 and thereby effect vertical movement of the table 32, without effecting movement of the sprocket gear 234 or any of the mechanism connected thereto.

The beveled gear 237, carrying the sprocket gear 236, is secured on the end of a stub shaft 243 rotatably mounted in a bearing 244 which is secured to the adjacent side frame 31 by studs 245, as illustrated in Fig. 11. This beveled gear 237 is driven by another beveled gear 246 secured on the end of a horizontal shaft 247 which is journaled at its rear end in the bearing bracket 244, as illustrated in Fig. 14. This shaft 247 is journaled in another bearing bracket 248 which is secured to the adjacent side frame 31 and projects outwardly therefrom as shown in Figs. 3 and 14. A crank handle 250 is slidably mounted in alignment with the outer end of the shaft 247 and has its hub 250^a slidably and rotatably mounted in a bearing block 249 carried by the side frame 31. The inner end of this hub 250^a carries a clutch disk 251 which is normally held in the position shown in Fig. 14 by a coil spring 252 seated in the recess 251^a of this disk and engaging at its other end the hub of a ratchet wheel 253 which is secured on the shaft 247. The clutch disk 251 and the hub 250^a of the crank member have a tubular bore, which is of non-circular cross-section in the hub of the crank member, so that it may form a non-rotatable engagement with the similarly formed extremity 247^a of the shaft when the crank handle and the clutch disk are moved toward the right, as shown in Fig. 14, against the compression of the spring 252. In this way, the crank handle 250 may be pushed inwardly and utilized for effecting a manual operation of the shaft 247 and the connected

train of mechanism by which the shaft 230 is operated so that the table 32 may be manually elevated to effect a precise positioning of the uppermost sheet of the stack 33 at the commencement of a printing operation.

For the purpose of automatically actuating the shaft 247 to effect a gradual elevation of the stack of paper sheets as the sheets are progressively withdrawn from the top of the stack, there is provided a cam 255 secured on the previously described power operated shaft 226 which is journaled in one of the bearing brackets 67 and also in a bracket 256 secured to the side frame 31, as shown in Fig. 3. As the shaft 226 is driven from the motor-operated shaft 160 through the sprocket chain 224, the cam 255 is rotated continuously and is adapted to control the operation of a lever arm 257 which is pivoted at 258 on the upper part of the adjacent bracket 67. This lever 257 is forced toward the face of the cam 255 by means of a spring 259 which is mounted on a rod 260. This rod is pivotally connected to the lower part of the lever 257 and is slidably mounted in a block 262 carried by the adjacent side frame 31. The coil spring 259 is mounted between this block 262 and a collar 263 secured on the rod so that when the lever 257 is oscillated about its pivot by the rotation of the cam 255, the spring 259 continually tends to move the lever 257 toward a position wherein the roller 261 mounted on the lever will engage the edge surface of the cam. The lower end of the crank arm 257 is pivotally connected to a link 265, as shown in Fig. 12, and this link extends downwardly and has a pivotal connection through a pin 266 with a pair of blocks 267 which are clamped by screws 267a on opposite sides of a pin 268 engaging a cylindrical aperture formed in these blocks and projecting from a sliding block 270 which is adapted to reciprocate in a slot 271a formed in an actuating member 271 rotatably mounted upon the shaft 247, as shown in Fig. 13. This actuating member 271 carries a screw 272 upon which is pivotally mounted a pawl 273 adapted to engage the teeth of the ratchet wheel 253 previously described. A coil spring 274 is mounted between the upper face of this pawl and a lug 275 formed on the side of the actuating member so that the spring maintains the pawl in engagement with the ratchet wheel. As the lever 257 is oscillated about its pivot 258, its motion is transmitted through the link 265 and the members 267 to the sliding block 270 which reciprocates in the slot 271a and causes the actuating member 271 to oscillate about the shaft 247. When this oscillation is sufficient in magnitude, the tooth 273a of the pawl engages a new tooth of the ratchet wheel 253 and causes angular motion of the shaft 247 through the distance represented by the length of one of the ratchet teeth. If the oscillation of the actuating member 271 is not of sufficient magnitude to cause the pawl to engage a new tooth, it merely rides back and forth on the face of the same tooth without effecting rotation of the shaft 247 upon which the ratchet wheel is secured. In order to prevent accidental rotation of the shaft 247 during the oscillation of the member 271 and to prevent reverse rotation of the shaft 247, that is, in a direction adapted to lower the table 32, there is provided a detent 277 which is adapted to engage the radial shoulder at the edge of one tooth and the long inclined side face of the adjacent tooth, as illustrated in Fig. 13. This detent 277 is carried by a stem 277a which is

slidably mounted in a sleeve 278 carried by a plate 279 attached to the adjacent side frame 31. This sleeve 278 has a threaded engagement with the plate 279 and may be locked in adjusted position by a nut 280. A pin 281 is connected to the stem of the detent 277 and extends through the bottom of the sleeve 278 where it has a fixed connection with a disk or handle 282 adapted to be manipulated for the purpose of withdrawing the detent from engagement with the ratchet wheel against the compression of the coil spring 273 which is mounted in the sleeve to bear against the stem of the detent and force it normally in an upward direction.

The extent of oscillation of the actuating member 271 and the frequency with which the pawl 273 engages a new tooth of the ratchet wheel 253 to effect angular motion of the shaft 247, is controlled by the elevation of the uppermost sheet of the stack of paper 33 through mechanism 257. This mechanism comprises a link 285 pivotally connected by a pin 286 with the upper arm of the lever 257 and also pivotally connected by another pin 287 with a crank 288 fixed on the end of a shaft 289 which is journaled at its ends in the brackets 67. At a point midway between the brackets 67, the shaft 289 carries a relatively fixed arm 290, provided at its outer end with an aperture which is adjustably engaged by a threaded rod 291 having a nut 292 mounted thereon below the arm 290 and a wing nut 293 mounted thereon above the arm 290. At its lower end this rod 291 has a head 291a which is pivotally connected to a link 294. This link is in turn pivotally connected to the outer end of a supporting arm 295 having a hub 295a which is pivotally mounted upon the shaft 230. This supporting lever 295 carries on the under side of its forward end a sleeve 295b in which is mounted a rod 296 capable of longitudinal adjustment therein and carrying a paper engaging bar 297. This bar extends downwardly and is adapted to contact endwise with the middle portion of the uppermost sheet of paper of the stack 33. The rod 296 may be adjusted in the sleeve 295b in order to position the bar 297 adjacent the middle portion of paper sheets of various sizes. With this construction, the shaft 289 is oscillated to elevate the bar 297 from the uppermost paper sheet each time that the cam 255 is rotated and the extent to which the roller 261 carried by the lever 257 is permitted to approach engagement with the flat side 255a of the cam is determined by the position of the paper engaging bar 297 when it is permitted to return to its lower paper engaging position shown in Fig. 20. When a sufficient number of paper sheets have been removed from the top of the stack to allow the bar 297 to be lowered to a position wherein the roller 261 is permitted to engage the flat side 255a of the cam, the amplitude of oscillation of the actuating member 271, actuated by the lever 257, will be great enough to permit the pawl 273 to engage a new tooth of the ratchet wheel 253, whereupon the next movement of the actuating member 271 causes a partial rotation of the shaft 247 and a corresponding elevation of the table 32 through the mechanism which connects the shaft 247 with the shaft 230. In this way, the extent to which the paper supporting table 32 is elevated is determined automatically by the rate of removal of paper sheets therefrom and is such that the upper surface of the uppermost sheet always occupies substantially the same level, within such

limits as will permit the proper functioning at all times of the vacuum cups 105 in engaging and gripping the forward edge of the uppermost sheet. From the foregoing description it will be seen that the suction head 35 has an intermittent rotary movement caused by the gears 196 and 197 so that at the end of each half revolution, it stops with the axes of the vacuum cups 105 directed vertically, as shown in Fig. 21. At this time the air blasts are directed against the forward portions of the upper sheets of paper through the blower tubes 88 and 89 so that the forward edge of the uppermost sheet is moved upwardly in a position to clear the upper ends of the guide stakes 55 and to be engaged by the lower ends 5 of the suction cups 105. As soon as this engagement occurs, the sleeves 110 of these suction cups move automatically upward because the lower ends of the cups are then sealed by the sheet 10 of paper and the atmospheric pressure acting on the under side of the paper sheet causes the sleeves 110 and the forward edge of the sheet to move upwardly. The gear 196 then causes another half revolution of the rotary head 35 with 25 the result that the uppermost sheet of paper is picked up and projected forwardly to the position shown in Fig. 22 without at the same time effecting any motion of the second sheet of the stack which is held securely in place by the retaining member 71. As the paper sheet is moved toward the position shown in Fig. 22, the paper gripping rollers 128 are held in elevated position, as shown in Fig. 21, by the cam 131, but when 30 the paper sheet and the engaging series of suction cups reach the position shown in Fig. 22, the suction is automatically shut off by the operation of the valve mechanism in the casing 100 or by the breaking of the connection between the connected tube 97 and the passage 91c in the bracket 91, or both, whereupon the rollers 128 35 are automatically lowered by the cam 131 so that the forward edge of the paper sheet is gripped between these rollers 128 and the roller 122. The paper sheet then moves rearwardly beneath the 40 guards 145 and beneath the rollers 150 as it is transported toward the printing cylinders by the operation of the continuously moving tapes 125. In this way, a new sheet of paper is lifted from the pack 133 and transported to the conveyor 36 45 upon each half revolution of the rotary head 35 and, as these sheets of paper are successively removed from the stack, the table 32 is automatically elevated by the actuating member 271 which has an amplitude of reciprocation dependent 50 upon the level of the uppermost sheet of paper. When the entire stack of paper sheets has been fed from the table 32, the hand wheel 232 may be pulled outwardly, after disengaging the latch member 240, to permit the free rotation of the shaft 230 in a reverse direction until the table 32 is lowered to a position where it may receive 55 a new stack of paper sheets.

Although one form of the invention has been shown and described by way of illustration, it will be understood that it may be constructed in various other embodiments coming within the scope of the appended claims.

I claim:

70 1. The combination in feeding mechanism for printing presses, of means for supporting a paper sheet, and a series of suction cups having a continuous path of travel and spaced apart along said path to engage said sheet at one point along 75 said path to move it from said supporting means,

said cups being movable transversely to said path independently of each other.

2. The combination in feeding mechanism for printing presses, of means for supporting a paper sheet, and a series of separate suction cups having intermittent motion along a continuous path of travel for engaging and picking up said sheet at one point along said path.

3. The combination in feeding mechanism for printing presses, of means for supporting a stack of paper sheets, and a series of separate suction cups having intermittent motion in a circular path and spaced apart transversely of said path for removing the paper sheets successively from said stack.

4. The combination in feeding mechanism for printing presses, of means for supporting a stack of paper sheets, and a suction device having intermittent motion in a circular path adjacent the upper part of said stack, said suction device comprising parts having relative radial movement for causing a portion of the uppermost sheet of said stack to adhere thereto when said device is stationary.

5. The combination in feeding mechanism for printing presses, of means for supporting a stack of paper sheets, and means comprising a plurality of separate movable suction cups following each other in a continuous path of travel and each having relatively movable telescoping parts which are movable independently of the other cups for removing said sheets successively from said stack.

6. The combination in feeding mechanism for printing presses, of means for supporting a stack of paper sheets, a suction device having intermittent motion in a circular path adjacent the upper part of said stack, said suction device having relatively movable parts for causing a portion of the uppermost sheet of said stack to adhere thereto and be picked up thereby when said device is stationary, and means for causing said sheet to be released by said suction device after continued movement thereof along said circular path.

7. The combination in feeding mechanism for printing presses, of means for supporting a paper sheet, a plurality of vacuum devices spaced apart and movable in a circular path for forming sealed engagements with said paper sheet when moving it from said support, and means for rendering some of said devices inoperative.

8. The combination in feeding mechanism for printing presses, of means for supporting a stack of paper sheets, a rotary suction head, and a cup carried by said head and adapted to be moved into sealed engagement with the uppermost sheet of said stack, said cup comprising parts adapted to have relative movement under the influence of atmospheric pressure when said seal is established to elevate said sheet from said stack.

9. The combination in feeding mechanism for printing presses, of means for supporting a stack of paper sheets, a rotary suction head, and a cup carried by said head and having telescoping parts one of which is movable by gravity into sealed engagement with the upper sheet of said stack when said head is in a predetermined position, said parts of said cup having relative movement under the influence of atmospheric pressure when said seal is established to elevate a portion of said sheet from said stack.

10. The combination in feeding mechanism for printing presses, of means for supporting a paper sheet, a rotary head comprising a plurality of

vacuum tubes, and a plurality of suction cups mounted on said tubes and movable independently of each other into engagement with said paper sheet.

5 11. The combination in feeding mechanism for printing presses, of means for supporting a paper sheet, a rotary head comprising a plurality of vacuum tubes, a plurality of suction cups mounted on said tubes and movable into engagement with said paper sheet, and means for imparting an intermittent rotary motion to said head and bringing it to rest when said cups on one of said tubes are in engagement with said sheet.

10 12. The combination in feeding mechanism for printing presses, of means for supporting a paper sheet, a rotary head comprising a plurality of vacuum tubes, a plurality of suction cups mounted on said tubes and movable into engagement with said paper sheet, means for imparting an intermittent rotary motion to said head and bringing it to rest when said cups on one of said tubes are in engagement with said sheet, and means for exhausting the air from each of said tubes when the cups thereon are in paper engaging positions.

15 13. The combination in feeding mechanism for printing presses, of means for supporting a paper sheet, a rotary head comprising a plurality of vacuum tubes, a plurality of suction cups mounted on said tubes and movable into engagement with said paper sheet, means for imparting an intermittent rotary motion to said head and bringing it to rest when said cups on one of said tubes are in engagement with said sheet, means for exhausting the air from each of said tubes when the cups thereon are in paper engaging positions, and means for relieving suction in each of said tubes after a predetermined movement thereof from the position in which the cups are carried thereby first engage said paper sheet.

20 14. The combination in feeding mechanism for printing presses, of a rotary head comprising a suction tube, means for rotating said head about a horizontal axis, means for supporting a stack 45 of paper sheets below the axis of rotation of said head, a suction device communicating with said tube and having a relatively movable part adapted to move into engagement with the uppermost sheet of said stack when in its lower position during the rotation of said head, and means for exhausting the air from said tube while said suction device is in engagement with said paper sheet.

25 15. The combination in feeding mechanism for printing presses, of a rotary head comprising a suction tube, means for rotating said head about a horizontal axis, means for supporting a stack 55 of paper sheets below the axis of rotation of said head, a suction device communicating with said tube and adapted to engage the uppermost sheet of said stack when in its lower position during the rotation of said head, and means for automatically exhausting the air from said tube as said suction device approaches said sheet and for relieving the vacuum in said tube after a predetermined movement of said head with said device engaging said sheet.

30 16. The combination in feeding mechanism for printing presses, of a rotary head comprising a suction tube extending parallel to the axis of rotation, a sleeve mounted on said tube, a suction cup carried by said sleeve, said tube having a port adapted to communicate with said suction cup, and means for securing said sleeve in adjusted position on said tube.

35 17. The combination in feeding mechanism for

printing presses, of a rotary head comprising a suction tube extending parallel to the axis of rotation, a sleeve mounted on said tube, a suction cup carried by said sleeve, said tube having a port adapted to communicate with said suction cup, means for securing said sleeve in adjusted position on said tube, means for rotating said head, and means for exhausting air from said tube during said rotation.

40 18. The combination in feeding mechanism for printing presses, of a rotary head comprising a suction tube extending parallel to the axis of rotation, a series of sleeves slidably mounted on said tube, a plurality of suction cups each mounted on one of said sleeves, said tubes having a series 15 of ports each adapted to communicate with one of said cups, and means for securing said sleeves in adjusted positions on said tube.

45 19. The combination in feeding mechanism for printing presses, of means for supporting a stack 20 of paper sheets, a rotary suction head, a plurality of suction cups carried by said head and adapted to form a sealed engagement with the uppermost sheet of said stack, and means for rendering some 25 of said suction cups inoperative.

50 20. The combination in feeding mechanism for printing presses, of a suction tube having a port therein, a sleeve slidably mounted on said tube and having an aperture adapted to register with said port when said sleeve is in proper position, a 30 vacuum cup mounted in said aperture in said sleeve, and means for securing said sleeve in adjusted position on said tube.

55 21. The combination in feeding mechanism for printing presses, of a rotary head comprising a 35 suction tube extending parallel to the axis of rotation, said tube having a series of ports therein, a sleeve slidably mounted on said tube and having a series of apertures therein, a plurality of suction cups each secured in one of said apertures, 40 each of said apertures being adapted to register with one of said ports, said sleeve being adjustable longitudinally of said tube to vary the number of apertures in registry with said ports, and means for securing said sleeve in adjusted position. 45

60 22. The combination in feeding mechanism for printing presses, of a rotary head comprising a suction tube extending parallel to the axis of rotation, said tube having a series of ports therein, a sleeve slidably mounted on said tube and having 50 a series of apertures therein, a plurality of suction cups each secured in one of said apertures, each of said apertures being adapted to register with one of said ports, said sleeve being adjustable longitudinally of said tube to vary the number of 55 apertures in registry with said ports, a rod extending parallel to said tube, and a clamp secured to said sleeve and engaging said rod for securing said sleeve in adjusted position.

65 23. The combination in feeding mechanism for printing presses, of a table for supporting a stack of paper sheets, a vertical guide stake engaging the forward edge of said stack, a side stake adapted to engage a lateral edge of said stack, means for removing said sheets successively from 65 the top of said stack, and adjustable guide members adapted to engage both lateral edges of said sheets adjacent the top of said stack.

70 24. The combination in feeding mechanism for printing presses, of means for supporting a stack 70 of paper sheets, a rotary suction head for engaging said sheets and removing them successively from the top of said stack, a roller onto which said sheets are delivered by said suction head, a shaft extending parallel to the axis of 75

said roller, an arm mounted on said shaft, a paper gripping roller carried by said arm and adapted to engage the upper side of a sheet on said first named roller, means for imparting an intermittent rotary movement to said head, means actuated in timed relation to the movements of said head for rocking said shaft to cause said gripping roller to engage each sheet as it is delivered to said first named roller, and means for adjusting said arm to compensate for different thicknesses of paper sheets.

25. The combination in feeding mechanism for printing presses, of a rotary suction head, a plurality of spaced suction cups mounted on said head, each of said cups comprising telescoping parts having relative movement radially of the axis of rotation of said head, said cups having parts movable outwardly by gravity when in the lower part of their path of travel around said axis of rotation and movable inwardly under the influence of atmospheric pressure when the outer portions of said cups are in engagement with a paper sheet, and spaced conveying rollers adapted to receive paper sheets delivered thereto by the suction cups of said head, said rollers being located in registry with the spaces between said suction cups.

26. The combination in feeding mechanism for printing presses, of means for supporting a stack 30 of paper sheets, a rotary head having means mounted on the intermediate portion thereof for engaging said sheets and removing them successively from the top of said stack, a conveying roller for receiving said sheets from said head, and 35 an apron extending rearwardly from said roller above the path of the sheets and having a downwardly deflected end portion adapted to guide the sheets to said roller.

27. The combination in feeding mechanism for 40 printing presses, of a rotary head comprising a suction tube having a port, a vacuum cup mounted on said tube and having communication through said port with said tube, and means for adjusting said cup angularly and longitudinally 45 of said tube while maintaining said communication.

28. The combination in feeding mechanism for printing presses, of a rotary head comprising a suction tube having a port, a sleeve mounted on 50 said tube, a vacuum cup carried by said sleeve to communicate with said port, and means for adjusting said sleeve angularly and longitudinally of said tube.

29. The combination in feeding mechanism for 55 printing presses, of a rotary head comprising a suction tube, a sleeve mounted on said tube, a vacuum cup carried by said sleeve, said tube having a port adapted to communicate with said cup, means including a clamp for securing said sleeve on said tube, and adjustable means for securing said tube on said clamp to permit angular adjustment of said tube.

30. The combination in feeding mechanism for 65 printing presses, of a rotary head comprising a suction tube, a sleeve mounted on said tube, a vacuum cup carried by said sleeve, said tube having a port adapted to communicate with said cup, means including a clamp for securing said sleeve on said tube, and adjustable means for securing said tube on said clamp to permit angular 70 adjustment of said tube, said port being formed to permit said cup to maintain communication with said port when said tube is adjusted angularly.

75. 31. The combination in feeding mechanism for

printing presses, of a rotary head, driving mechanism for rotating said head including a gear, and a second gear for driving said first named gear, said second gear having gear teeth throughout a portion only of its periphery whereby an intermittent motion is imparted to said head. 5

32. The combination in feeding mechanism for printing presses, of a rotary head, means including a gear for rotating said head, said gear having two series of teeth each extending through substantially one-half of the periphery of said gear, and a driving gear having teeth throughout one-half of its periphery only for meshing successively with the series of teeth carried by said first named gear for imparting an intermittent 15 rotary motion to said head.

33. The combination in feeding mechanism for printing presses, of a rotary head, driving mechanism for rotating said head including a gear, a second gear for driving said first named gear, said second gear having gear teeth throughout a portion only of its periphery whereby an intermittent motion is imparted to said head, and means for preventing shock when the teeth of said second named gear first engage the teeth of said first 25 named gear.

34. The combination in feeding mechanism for printing presses, of a rotary head, driving mechanism for rotating said head including a gear, a second gear for driving said first named gear, said 30 second gear having gear teeth throughout a portion only of its periphery whereby an intermittent motion is imparted to said head, one of said gears being provided with shoulders, and resiliently mounted dogs carried by the other gear 35 for engaging said shoulders to prevent shock.

35. The combination in feeding mechanism for printing presses, of a rotary head, means for rotating said head including a gear having two series of teeth connected by an arcuate surface, 40 a second gear having a series of teeth extending throughout a portion of its periphery to mesh with the teeth of said first named gear and having an arcuate surface adapted to coact with said arcuate surface of said gear when said head is 45 stationary, and means for continuously rotating said second named gear.

36. The combination in feeding mechanism for printing presses, of a rotary head, means for rotating said head including a gear having two 50 series of teeth connected by an arcuate surface, a second gear having a series of teeth extending throughout a portion of its periphery to mesh with the teeth of said first named gear and having an arcuate surface adapted to coact with said 55 arcuate surface of said gear when said head is stationary, means for continuously rotating said second named gear, one of said gears having projecting shoulders, and dogs resiliently mounted on the other of said gears and adapted 60 to engage said shoulders when the teeth of said second named gear move into mesh with the teeth of said first named gear.

37. The combination in feeding mechanism for printing presses, of a rotary head, means for 65 rotating said head including a gear having two series of teeth connected by an arcuate surface, a second gear having a series of teeth extending throughout a portion of its periphery to mesh with the teeth of said first named gear and having an arcuate surface adapted to coact with said 70 arcuate surface of said gear when said head is stationary, means for continuously rotating said second named gear, one of said gears having projecting shoulders, and dogs resiliently mounted 75

on the other of said gears to engage said shoulders for relieving shock when said teeth of said second gear move into mesh with the teeth of said first named gear.

5 38. The combination in feeding mechanism for printing presses, of a rotary head, means for rotating said head including a gear having two series of teeth connected by an arcuate surface, a second gear having a series of teeth extending 10 throughout a portion of its periphery to mesh with the teeth of said first named gear and having an arcuate surface adapted to coact with said arcuate surface of said gear when said head is stationary, means for continuously rotating said 15 second named gear, one of said gears having projecting shoulders, dogs resiliently mounted on the other of said gears and adapted to engage said shoulders when the teeth of said second named gear move into mesh with the teeth of said

first named gear, springs engaging said dogs to permit said dogs to yield when they engage said shoulders, and means for adjusting the initial compression of said springs.

39. The combination in feeding mechanism for printing presses, of means for supporting a pile 5 of sheets, a rotary vacuum head having suction cups adapted to come to rest and engage the uppermost sheet of said stack at the end of each half revolution of said head, and driving means 10 for said head comprising a pair of gears, one of said gears comprising two series of gear teeth each extending throughout substantially one-half of the periphery of the gear, the other of said gears comprising one series of teeth extending 15 throughout substantially one-half of its periphery and adapted to mesh with the series of teeth carried by said first named gear.

ALEXANDER T. KOPPE.
